UNITED STATES PATENT OFFICE

2,085,280

VALVE SEAT GRINDER

Merle D. Tyler, Chicago, Ill.

Application November 1, 1934, Serial No. 750,963

3 Claims. (Cl. 51—185)

The present invention relates to valve seat grinders and is particularly concerned with grinders of the type adapted to be used in grinding extremely hard valve seats of internal combustion engines, such as, for example, the high speed tungsten or stellite steel valve seat inserts now being used.

One of the objects of the invention is the provision of an improved valve seat grinding tool which may be manufactured at a very low cost and which is adapted to be utilized in grinding very hard valve seats.

Another object of the invention is the provision of an improved grinder which is simple in construction and requires a minimum amount of machine work in its manufacture.

Another object of the invention is the provision of an improved valve seat grinder which is sturdy and serviceable, accurate, and which may be manufactured at such a low cost that it may be purchased by a vast number of users who otherwise could not afford to purchase tools of this type.

Another object of the invention is the provision of an improved valve grinder of the class described which is adapted to be used in relatively inaccessible places, such as on the valve seat located under an overhanging dash.

Another object of the invention is the provision of an improved valve seat grinder of the class described in which the grinding member may be quickly renewed.

Another object of the invention is the provision of an improved valve seat grinder of the class described in which the grinding member consists of a thin strip of fabric or paper covered with abrasive particles and so shaped that the strip is continuous in the direction of rotation about the surface of the grinder.

Another object of the invention is the provision of an improved valve seat grinder of the class described having a facing of flexible abrasive material in which the flexible facing is resiliently secured in place so as to insure its being shaped perfectly by the supporting body.

Other objects and advantages of the invention will be apparent from the following description and from the accompanying drawing, in which similar characters of reference indicate similar parts throughout the several views.

Referring to the single sheet of drawings accompanying this specification,

Fig. 1 is a side elevational view of a valve seat grinder constructed according to the present invention, shown in connection with an internal

combustion engine block, the block being in section;

Fig. 2 is a top plan view of the valve seat grinder;

Fig. 3 is a sectional view taken on the plane of the line 3—3 of Fig. 2, looking in the direction of the arrows, with parts of the driving shaft in section and other parts in elevation;

Fig. 4 is a bottom plan view of the valve seat grinder, with the pilot in section, on the plane of the line 4—4 of Fig. 3, looking in the direction of the arrows;

Fig. 5 is an exploded view of the parts of the grinder, showing a fragment of the pilot and a fragment of the drive shaft;

Fig. 6 is a plan view of the abrasive covering sheet.

Referring to the drawing, 10 indicates in its entirety the complete grinding equipment, which preferably consists of a motor such as a drill motor 11 having a chuck 12, a drive shaft 13, the grinder 14, and a pilot 15.

The equipment is shown in connection with an internal combustion engine block 16, which is provided with a relatively hard valve seat insert 17, and the usual valve stem guide 18. A number of different pilots 15 are provided, the sizes being suitable so that the pilots, which are accurately finished to cylindrical shape, may be rotatably mounted in the valve stem guides 18 of various types of engines which have guides of different sizes. The valve stem pilots 15 fit the guides 18 closely enough to center accurately the grinder 14 with respect to the seat 17 and with respect to the axis of the valve stem guide 18.

All of the pilots are preferably provided with a reduced threaded portion 19 of the same size and preferably having right hand threads so that the tendency is for the pilot 15 to be threaded home into the body of the grinder 14 when the shaft is rotated in a right hand direction.

An annular shoulder 20 is located between the reduced threaded portion 19 and the cylindrical body of the pilot 15, and is adapted to engage a clamping member or spider 21, which is utilized for securing the flexible abrasive element 22 on the body 23 of grinder 14.

The drive shaft 13 is preferably, but not necessarily, provided with a flexible shaft portion 24 located between two shaft sections 25 and 26 so that the grinder may be used in relatively inaccessible places by disposing the drive shaft of the motor 11 at an angle, as shown in Fig. 1, under the over-hanging dash 27.

The flexible shaft portion 20 may consist of 55

a fairly heavy helical spring having its coils close together and secured to the reduced ends 28, 29 of the shafts 25, 26 respectively. This coil spring may be secured to the reduced ends 5 28, 29 in any of a number of different ways, such as, for example, by providing the reduced portions 28, 29 with relatively rough threaded formations of such shape that the coil spring 24 may be threaded over the spring, being threaded 10 ed home against the annular shoulders 30, 31.

The size of the cylindrical parts of the shafts 25 and 26 and the size of the reduced portions 28 and 29 are such that when the spring 24 is located on the reduced portions 28, 29 the outer 15 surface of the spring is flush with the cylindrical surfaces of the shafts 25, 26.

The springs may also be secured in place in some embodiments of the invention by making the reduced portions 28, 29 slightly larger than 20 the space inside the spring 24 and forcing the springs on the reduced cylindrical portions 28, 29 where they are secured by the frictional grip of the springs against the ends of the shafts. For this purpose the reduced portions 28, 29 may be 25 slightly tapered, if desired.

Springs secured in either of the modes just described may be further permanently secured by welding, soldering, or otherwise forming a 30 relatively integral bond between the parts of the flexible shaft 24 and the shafts 25, 26. The lower end of drive shaft 26 is also provided with a reduced threaded portion 32 and with an annular shoulder 33 for use in securing the shaft to the body 23 of the grinder 14.

35 The threaded portions 19 and 32 are preferably of the same size so that the aperture or bore 34 in the grinder body 23 may be of the same size throughout and provided with threads of the same characteristics for fitting both the 40 end of the shaft 26 and the end of the pilot 15. Thus the body 23 may be threaded at one time for attachment of the shaft 26 above and the pilot 15 below.

The grinder body 23 is preferably formed of 45 die cast metal in a casting operation, and is provided with a plurality of frusto-conical surfaces 35, 36, 37, 38, separated by slots 39. These sections of frusto-conical surfaces 35-38 all form parts of the same frusto-conical surface and 50 correspond in angularity to the angularity of the valve seat upon which the grinder is to be used, such as, for example, forty-five degree valve seats, sixty degree valve seats, or thirty degree valve seats. Obviously, grinders of any angularity may 55 be made, and those just listed are merely exemplary of the most common shapes.

At its lower end the grinder body 23 is provided with a flat surface 40, which is adapted to engage the inner flat side of the clamping member or spider 21. At its upper end the valve seat body 23 is preferably provided with a flat upper surface 41 which may be engaged by tool holders in some types of driving equipment, and on other occasions it may be engaged by the driving 60 end of an ordinary valve seat lapping machine. For this purpose the upper flat surface 41 is provided with the pairs of holes 42, 43 which perform the same function as the slot or holes in the upper end of the valve stem for receiving the projecting ends of the plate on the end of a geared valve seat grinder of the type which rotates the valve or grinder forward and backward.

Body 23 of the grinder is preferably longer 75 or deeper in a vertical direction than the dimen-

sion necessitated for the frusto-conical surfaces 35-38, and is therefore generally provided with a cylindrical outer surface 44. Since a considerable portion of the body is removed in forming the slots 39, it is also desirable to provide the 5 body 23 with a cylindrical boss 45 at its upper end, thereby giving the body greater strength and providing more material for joining the frusto-conical parts 35-38 together.

The clamping member or spider 21 preferably consists of a spring steel member which may be made of non-corrodible material, such as stainless steel, or from ordinary spring steel. It is preferably provided with a centrally located aperture 46 for passing the reduced threaded end 15 19 of the pilot 15, and with an annular body 47.

Projecting radially from the annular body 47 are a plurality of integral strips or spring fingers 48 which have been bent upward from the annular body 47 at the points 49 in such manner 20 as to engage the flexible abrasive covering 50 and draw it taut on the frusto-conical surfaces 35, 38.

As observed in Fig. 3, the angularity of the 25 spring fingers 48 is such that any excess of flexible abrasive over that required to cover the frusto-conical surfaces 35-38 is drawn into the slots 39. While the fingers 48 are resilient, they are of sufficient thickness and stiffness so that the flexible abrasive material is secured with sufficient firmness so that there is no possibility of its becoming loose under operation. However, the proportions of the annular abrasive covering 50 and the grinder body 23 are such that the abrasive becomes tight slightly before the clamping member 21 meets the lower end 40 of the body 23, and the spring fingers 48 are slightly flexed and placed under tension when the clamping member 21 is driven home against the end 40 by the annular shoulder 20 of pilot 15.

The abrasive covering 15 may consist of any 40 form of flexible abrasive having a paper or fabric base, the latter being preferred on account of its greater flexibility and greater tensile strength. Therefore, the abrasive covering 50 45 preferably consists of emery or carborundum cloth in the form of an annulus, as shown in Fig. 6.

It should be observed that the aperture 51 in the annulus 50 is larger in the blank pattern 50 than it appears in plan, when the slack has been taken up, and the abrasive is secured to the body 23 as shown in bottom plan in Fig. 4.

It will thus be observed that I have invented an improved and simplified structure in which the abrasive is resiliently yet firmly secured so that it may be conveniently removed and replaced, and it is not necessary to provide a complete grinding stone, since merely the outer surface may be provided with abrasive. The pilot 60 is used for directly securing the abrasive covering to the grinder body by means of the resilient clamping member 21, and when the pilot is driven home sufficient tension is placed upon the flexible abrasive covering. The grinder may 65 be provided with a flexible upper shaft at a minimum expense, by means of the structure described, and the machining operations involved are reduced to a minimum, since the body of the grinder may be cast, and it is only necessary 70 to thread the aperture in the body.

While I have illustrated and described a preferred embodiment of my invention, many modifications may be made without departing from the spirit of the invention, and I do not wish 75

to be limited to the precise details described, but desire to avail myself of all changes within the scope of the appended claims.

What I claim as new and desire to secure by Letters Patent of the United States is:

- 5 1. In a tool for grinding valve seats, the combination of a supporting body having a substantially frusto-conical backing surface, said body being formed with a plurality of radially and inwardly extending slots, each of said slots extending substantially in the direction of an element of said frusto-conical surface located at said slot, a flat annulus of flexible abrasive material carried by said body in engagement with said backing surface, said annulus having its slack taken up by extending into said slots, and a relatively stiff yet resilient metal member centered on said body outside said annulus and having a plurality of legs, each of said legs extending 10 into one of said slots, and forcing said slack abrasive into said slots, said legs holding said annulus taut against said frusto-conical surface by virtue of the resiliency of said legs, which are adapted to be flexed to maintain a predetermined 15 tension on said abrasive, said body having a threaded bore, a pilot member having a reduced threaded section adapted to be threaded home in said bore, said metal member having an aperture receiving said reduced threaded section, and 20 said pilot having a shoulder engaging said metal member to clamp said metal member against said body when said legs are placed under tension.
- 25 2. In a tool for grinding valve seats, the combination of a metal body provided with a plurality of substantially frusto-conical surfaces formed with the same generatrix and spaced from each other by a plurality of radially inwardly extending slots, said body having a substantially flat upper surface and being provided with a centrally located threaded bore on its frusto-conical side, a flexible abrasive annulus of sufficient size so that when it is placed upon the frusto-conical surfaces of said body and substantially conformed thereto said frusto-conical surfaces will be substantially covered and the slack of said annulus extend into the slots, the depth of said slots being sufficient with respect to the amount of slack in said annulus so that the base of the slots will not prevent the abrasive from being drawn taut 30 on said frusto-conical body, a metal spider having a centrally located aperture for registry with said threaded bore, and having a plurality of radially extending arms, one arm extending into each of said slots, and said arms extending diagonally from the body of said spider in substantially the direction of the base of said slots, said arms being bent at an angle whereby they are adapted to engage the abrasive annulus and take up all of the slack therein and draw the annulus taut on the frusto-conical body when the spider is driven into said slots, and a pilot having a threaded end and a shoulder for engaging said spider, said threaded end being located in said threaded bore whereby said pilot is adapted 35 to exert the tensioning force by driving said spider in an axial direction toward said body, said threaded bore extending through said body, and a drive shaft comprising a threaded metal rod driven home in the upper end of said bore, 40 said rod having a spirally wound flexible section secured thereto and a second drive rod for grip by a chuck carried by the other end of said spiral flexible section.

MERLE D. TYLER. 55
